MOVABLE SHIELD STRUCTURE FOR
VACUUM GAP DEVICES

James D. Cobine, Rexford, N.Y., assignor to General
Electric Company, a corporation of New York
Filed Feb. 23, 1962, Ser. No. 176,485
11 Claims. (Cl. 209—143)

This invention relates to an improved vacuum device construction wherein a shield element is provided to protect the vacuum envelope from condensation and nevertheless the electrodes can be visually examined at will.

This application is a continuation-in-part of my prior application Serial No. 79,351, filed December 29, 1960, now abandoned.

In vacuum devices such as switches, circuit breakers and vacuum gaps, a vacuum envelope is provided and defines a vacuum cavity. A pair of electrodes is located within the envelope and have portions extending outside the same for connection to the circuit to be switched or protected. The electrodes are movable in relation to each other between a contact-making or circuit-making position and a contact-breaking or circuit-interrupting position in the case of switches and are spaced to define a gap in fixed gap devices. When the electrodes are moved in relation to each other from circuit-making to circuit-breaking position or when a fixed gap is overloaded, an arc is usually drawn. The arc gives rise to some vaporization of the electrode materials and subsequent condensation thereof. The condensation takes place on the electrodes, on the inside face of the vacuum cavity, and on other parts exposed to the vapor. In devices designed to carry current until natural current zero (and thus avoid the overvoltages associated with abrupt current interruption), the electrodes are designed to provide copious quantities of vaporized material, thus giving rise to a considerable amount of condensation.

When condensation of the electrode material takes place on the inside face of the vacuum envelope, it tends to form a conducting current path across otherwise insulating portions of the envelope. These insulating portions of the envelope must retain their insulating integrity. Otherwise conduction across the switch may take place even though the electrodes are in a spaced, non-contacting relationship.

In one method of preserving the insulating integrity of the inside face of the vacuum envelope, a shield is located between the electrodes and the vacuum envelope. Conventionally, the shield is in the form of a cylinder about the electrodes. Frequently, inwardly flaring end portions are provided to confine the vapor further. The shield is of material and conformation to define a favorable surface for the condensation of the electrode material vapor. Typically, the shield is of stainless steel.

The ability of a vacuum switch to withstand rapid circuit voltage recovery depends in considerable measure on the condition of the electrodes. When the electrodes are smooth and devoid of pitting and erosion, the circuit interrupting capacity is at a maximum. As the condition of the electrodes deteriorates with continued use of the device, the irregularities on the surfaces of the electrodes form points of abnormally high voltage gradient, with the result that the operating capacity of the device is reduced. It is accordingly important to inspect such switches and gap devices periodically to assure that electrode deterioration has not reached a point wherein the operating capacity thereof is unduly prejudiced. This is especially true in the case of switch or gap device having electrodes with tin, copper, and similar low vapor pressure ingredients and hence relative great susceptibility to electrode erosion.

In accordance with the present invention, the vacuum device envelope has at least some portion of transparent material, such as glass. The electrodes are so located

2

within the envelope as to be viewed readily through this transparent portion, thus permitting the user to ascertain the condition of the electrodes through visual inspection. At least one movable shield element is interposed between

5 the electrodes and the transparent portion of the vacuum envelope. This is movable between two positions. One position is the active position in registration with the transparent part of the envelope. In this position the shield element is effective to protect the transparent portion of
10 the envelope from condensation of the vaporized electrode material. The other position is the viewing position, where the shield element is out of registration with the transparent part of the envelope and thus permit uninterrupted view of the electrode from outside the envelope.

15 The present invention also contemplates various specific constructions through which the above movable electrode action is achieved.

It is therefore a general object of the present invention to provide improved vacuum devices using shield elements
20 and in which the condition of the electrodes may be visually examined at will.

Another object of the present invention is to provide improved vacuum devices of the foregoing type wherein movable shield elements cooperate with transparent envelope portions to permit visual electrode examination
25 at will.

Still another object of the present invention is to provide an improved vacuum switch using movable shield elements in cooperation with transparent envelope portions and in which apparatus extending outside the envelope is effective in cooperation with apparatus in the envelope to move the shield elements from active to inspecting position.

Another object of the present invention is to provide an improved vacuum device using movable shield elements telescopically disposed within the vacuum envelope and movable over the inside face thereof between active and inspecting positions.

Yet another object of the present invention is to provide an improved vacuum switch using movable shield elements and including cooperating electrode and shield parts effective to move the shield from active to inspecting position upon predetermined electrode movement.

Another specific object of the present invention is to provide an improved vacuum device having two-part shield means in which one part defines a port in registration with a transparent portion of the envelope to permit viewing of the electrodes and the other part is a cover movable between an active position covering the port and an inspecting position out of registration with the port.

Further objects of the present invention include the provision of improved vacuum devices having shield elements movable between active and viewing positions, effective in active position to prevent undesirable condensation on insulating parts and effective in viewing position to permit viewing of the electrodes, and embodying features of construction, combination and arrangement rendering them suitable for practical use under a wide variety of conditions, readily manufactured, reliable, and in other respects forming commercially useful and desirable devices.

The novel features which I believe to be characteristic of my invention are set forth with particularity in the appended claims. My invention itself, together with further objects and advantages thereof, will best be understood by reference to the following description taken in connection with the accompanying drawings, in which:

FIG. 1 is a view in axial cross-section with parts in elevation a vacuum switch constructed in accordance with the present invention with the shield shown by dashed lines when in viewing position.

FIG. 2 is a cross-sectional view through axis 2—2, FIG. 1, showing the arrangement of the ferromagnetic bars or armatures about the shield.

FIG. 3 is a greatly enlarged fragmentary portion of FIG. 1, showing the roller construction in further detail.

FIG. 4 is a view like FIG. 3, but shows a ball and socket construction alternative to the roller construction of FIG. 3, illustrative of the various means that may be employed to position the shield and permit free vertical movement thereof.

FIG. 5 is a fragmentary view like FIG. 1, but showing an alternative form of the present invention; with the shield shown by dashed lines when in viewing position.

FIG. 6 is a fragmentary cross-sectional view through axis 6—6, FIG. 5.

FIG. 7 is a fragmentary side elevational view, with parts in diagrammatic form, showing another alternative construction of the present invention in which the shield has a stationary part defining a window and a movable part which in active position registers with the window and in viewing position is out of registration therewith.

FIG. 8 is a somewhat diagrammatic cross-sectional view of an alternative embodiment of the structure of FIG. 7.

FIG. 9 is a greatly enlarged fragmentary portion of FIG. 8, showing the bearing means in the knob to provide for rotation of the arm which terminates therein.

FIG. 10 is a view in fragmentary form, like FIG. 1, but showing still another embodiment of the present invention.

FIG. 11 is a cross-sectional view through axis 11—11, FIG. 10.

FIG. 12 is a view like FIG. 10 but showing the parts in circuit-breaking position.

FIG. 13 is an enlarged fragmentary view taken along axis 13—13, FIG. 10.

FIGS. 14 and 15 are vertical cross-sectional views of a vacuum gap device of the fixed type constructed in accord with another feature of the invention.

Referring now to FIG. 1, there is shown at 1 a vacuum envelope defining a cylindrical vacuum space 2. This envelope, as shown, is of insulating material such as glass and receives at its inturned upper end the sleeve 3, which is preferably of fernico and is embedded in the beaded inturned edge of the envelope as shown. Alternatively envelope 1 may be of metal with suitable bushings to insulate electrode rods therein from one another. At its lower outturned beaded edge, the envelope receives the end cap 4, which is likewise embedded and is preferably of fernico. The sleeve 3 receives one end of the bellows 5 in a vacuum-tight seal. The other end of bellows 5 is in vacuum-tight seal with the movable electrode rod 6. The end cap 4 is in vacuum-tight seal with the fixed electrode rod 7, thereby completing the vacuum envelope around the space 2.

Electrode rods 6 and 7 are each of generally cylindrical construction extending coaxially of the envelope from outside the envelope to their respective headed electrodes 8 and 9, which are in cooperating positions within the envelope. The electrode rods receive circuit connection 10 and 11, respectively, to the external circuit to be controlled. (not shown).

The electrode rods 6 and 7 are shown in the spaced circuit-breaking position in FIG. 1. That is, the electrodes 8 and 9 are out of contact with each other and the vacuum space defines an insulating barrier between the electrodes. When circuit conduction is desired, the electrode rods 6 and 7 are moved in relation to each other to bring the electrodes 8 and 9 to contacting relation. This is done by moving the upper electrode rod 6 down as permitted by the bellows 5 until contact is made between electrodes 8 and 9. Suitable means (not shown) is provided to sustain the movable electrode rod

6 in position and to move the same as desired between circuit-making and circuit-breaking position.

When the electrodes are moved from circuit-making to circuit-breaking position, an arc is usually struck therebetween and continues momentarily. This results in the production of quantities of vaporized electrode material. In the apparatus of FIG. 1, this material tends to condense on the interior surface of the shield 12, rather than on the adjacent interior faces of the envelope 1. To this end, the shield 12 is of cylindrical construction as shown in FIGS. 1 and 2 to define a cylindrical segment of the envelope 1 that is aligned with the electrodes and is protected from condensation. The shield 12 flares inwardly at 13 and 14 to define restricted end portions that further limit the extent that vaporized electrode material is free to condense on the interior of the vacuum envelope. It is rolled at the end to minimize arcing.

The shield 12 is movably positioned within the vacuum envelope 1. It has a plurality of outwardly extending arms 15, each carrying a wheel 16 shown in greater detail in FIG. 3 (or an equivalent means facilitating lateral motion). As shown in FIGS. 1 and 2, these arms may be in two axially spaced groups of four each, thus locating the shield in aligned, centered position in the cylindrical envelope. Alternatively, these arms 17, as shown in FIG. 4, may extend outwardly from the shield and terminate in socket portions 18, each of which receives a ball 19 to roll on the cylindrical envelope and similarly locate the shield in aligned, centered positions on the cylindrical envelope.

A plurality of ferromagnetic bars or armatures 19a are located about the periphery of the shield 12 as shown in FIGS. 1 and 2. Preferably these are oriented to define elements of a cylinder and are of sufficient number to form in effect a sleeve about the shield 12. The respective armatures are anchored on the shield by the ears 20, as shown in FIG. 2.

Outboard the vacuum envelope there is provided the shield operating mechanism shown generally at 21. This mechanism is composed of bearing 22, arm 23 longitudinally slid able in the bearing, handle, or knob 24 on the lower end of the arm 23, and permanent magnet 25 carried by the head member 26 on arm 23. As shown, the magnet 25 defines a pair of opposite permanent magnet poles spaced to register with the upper and lower margins of the armature elements 19a. Preferably, the magnet 25 extends in close proximity to the outer face of the envelope 1 and the armature 19a extend to closely spaced relationship with the inner face of the envelope 1 so as to cause a maximum quantity of the flux of magnet 25 to extend through the armatures.

The shield is movable between an active and a viewing position. The active position is shown in the solid lines of FIG. 1. In this position the shield 12 is axially aligned with the electrodes 8 and 9 and is thus interposed between the transparent side of the envelope 1 and the electrodes. In this position the shield is effective to protect the portion 27 of the envelope from condensation of vaporized electrode material. The shield 12 is normally in this active position and thus is effective when circuit-breaking operations take place.

The other position of shield 12 is the viewing position. This is the position shown in the dotted lines of FIG. 1. When in this position, the upper edge of the shield is below the upper face of electrode 9 and the electrodes may both be readily visually inspected by the user.

The shield 12 is moved between the active and inspecting positions by appropriate motion movement of the knob 24 of arm 23. When this arm is in the up position (as shown by the solid lines of FIG. 1), the magnet 25 is elevated and, through the magnetic attraction between the magnet 25 and the armatures 19a, sustains the shield in the active, elevated, position as shown. As the arm 23 is drawn downwardly, the shield is likewise car-

ried down by the reason of the magnetic attraction between the magnet 25 and the armatures 19a, thus bringing the shield to the lowered or inspecting position. When the arm 23 is subsequently raised the magnetic attraction causes the shield to lift with it, restoring the parts to the solid line positions of FIG. 1.

It will be noted that the armatures 19a are located at substantially uniform peripheral spacings and are relatively close together. This assures that effective magnet attraction exists between the magnet 25 and the armatures 19a, irrespective of the position of rotation of the shield within the envelope 1. It is thus unnecessary to confine the shield insofar as its position of rotation is concerned, and it may, as shown, be free to rotate within the envelope.

FIGS. 5 and 6 show an alternative form of the structure of the present invention. In this construction the envelope 1 defines a vacuum space 2 within which the electrode rods 6 and 7 and electrodes 8 and 9 are disposed as described above in relation to FIG. 1. A pair of cylindrical shield members 28 and 29 are disposed within the vacuum space 2, as shown in FIGS. 5 and 6. Each of these shields is of stainless steel or similar material and encircles the axis of the switch as shown. The upper edge or lip 30 of the lower shield 29 forms an annular edge as shown. The lower edge or lip 31 of the upper shield 28 telescopes within lip 30 as shown to provide an uninterrupted shielding surface about the electrodes when shields 28 and 29 are in the positions having no end-to-end spacing as shown by the solid lines of FIG. 5.

Each shield 28 and 29 has a plurality of magnetic bars or armatures 32 disposed about its periphery as shown. These coat with the respective magnets 34 to provide magnetic attraction holding the shields in axial registration with the respective magnets. Each magnet 34 is mounted on a carrier 35 having a threaded bore which receives the screw 36, which in turn is mounted on bearings 37 and is turnable through the rotation of the knob 38. Each magnet 34 is held by means (not shown) to prevent it from rotating with the frictional forces of rotating shaft 36.

Shields 28 and 29 are moved to the retracted position defining end-to-end spacing by rotation of the knob 38. This causes the carriers 35 to move the magnets 34 away from each other by reason of the respective right and left hand pitch of the screw mechanism. With the shields 28 and 29 in the retracted or end-to-end spaced positions, the axial space between the lower edge 31 of the upper shield 28 and the upper edge 30 of the lower shield 29 permits the user to view the electrodes and thereby ascertain their condition.

It will be appreciated that, although in the embodiments of FIGS. 1 and 5, specific switch-associated magnetic means for moving the shield have been shown, such means are not essential to the switch itself and other magnetic means, not associated with the switch, may be utilized. Similarly, in these embodiments, many friction-reducing means, other wheels or bearings may be used to facilitate movement of the shield within the switch. Thus, for example, spring biased fingers may bear against the switch inner walls. Means (not shown) are provided for preventing the control magnets from rotating as the control shaft is rotated.

FIG. 7 shows another form of the present invention. In this construction the envelope 1 defines a vacuum space 2 within the electrode rods 6 and 7 and electrodes 8 and 9 are disposed as described above in relation to the embodiment of FIG. 1. In the embodiment of FIG. 7, a two-part movable opaque shield 39 is disposed between the inside face of the envelope 1 and the electrodes 6 and 7. The shield is of stainless steel or a similar material.

One part of the shield 39, indicated at 40, is in the form of a cylinder immovably disposed within the envelope 1 between the electrodes 8 and 9 and the envelope

1 to protect portions of the envelope from condensation of the vaporized electrode material. An opening or window 41 is provided in the wall of the fixed part 40 of the shield 39 in registration with electrodes 8 and 9. The electrodes may be viewed through this window.

The other part of the shield 39 is a cover portion 42 adaptable to cover the opening 41 in the fixed portion 40 of shield 39. The cover portion 42 of the shield 39 is movable between an active position in registration with the opening 41 in the fixed shield 40 (as shown in solid lines in FIG. 7) and a viewing position out of registration with the opening (as shown in dotted lines in FIG. 7). This motion is made by actuating lifting button 45. The arm 46 and the crank arm 43 are interconnected by lever 47. Lever 47 is pivotally connected to crank arm 43, which pivots about fixed pivot 44. At its opposite end the lever 47 is similarly pivoted to the arm 46, as shown. At intermediate point 47a lever 47 is supported by a slidable pivot, thus causing lever 47 to rotate clockwise and crank 43 to rotate counterclockwise as the arm 46 is lifted. The lengths of the respective lever arms provide amplification of movement between the lifting movement of arm 46 and the resultant swinging movement of the crank 43, thus bringing the shield 42 out of registration with window 41 (as shown in the dotted lines) when the button 45 is moved a relatively small distance. The operator can then view electrodes 8 and 9 and evaluate the condition of the same. When the electrodes have been inspected, the push button 45 is moved downwardly by its weight and by spring 50a to restore part 42 to shielding position.

Arm 46 extends through opening 48 in the glass envelope 1. A sleeve 49, preferably of ferrico, is embedded in envelope 1 at this opening and receives bellows 50 to define a vacuum-tight seal over opening 48 and extending about the end of arm 46. Button 45 engages the closed end of the bellows 50 to push the same upwardly to raise arm 46 as desired.

Another modification of the present invention is shown in FIG. 8. In this form of the invention a two-part movable opaque shield, shown generally at 52, is located between the inside face of the envelope 1 and the electrodes 8 and 9 in much the same fashion as shown and described with respect to the embodiment of FIG. 7. In the construction of FIG. 8, the two-part shield is composed of a fixed part 51, immovably mounted by suitable support elements (not shown) and a movable portion 52. An opening or window 54 is provided in the fixed part 51 of the shield unit 52 to permit viewing of the electrodes.

The movable portion of the shield 52 is comprised of a cover 53. This cover is adapted to register with and cover the opening 54 in the fixed part 51 of the shield. It is attached to a crank arm 55 which is rotated to move cover 53 between an active position in registration with the opening 54 and a viewing position wherein said movable portion is out of registration with the opening. The arm 55 is rotatably supported by bearing 56, which is mounted in the wall of the envelope 1 as shown.

The arm 55 has an external bent operating portion 57. The arm 55 terminates in a knob 58, which is rotatably supported thereon by bearings 59, as is more clearly shown in FIG. 9.

A vacuum-tight seal is provided about the opening in the envelope 1 in which the bearing 56 is mounted. This seal is defined by sleeve 60, preferably of ferrico, which is embedded in envelope 1, as shown. One end of a bellows 61 is attached to this sleeve in a vacuum-tight seal. The opposite end of the bellows 61 is affixed in vacuum-tight seal to the knob 58, thereby completing the vacuum seal around the opening for the bearing 56 in the envelope 1.

The movable shield part 53 is moved between the active and inspecting positions by rotation of the knob 58 about the orbit defined by the offset of arm 55. It should be observed that the bellows 61 and knob 58 do

not rotate with respect to the envelope 1, so that a fixed sealing relationship between these parts is provided. Rather, the arm 55 rotates within the knob 58 reason of the bearings 59.

FIGS 10-13 are illustrative of still another embodiment of the present invention.

The fragmentary view of FIG. 10 shows a cylindrical envelope 1 which defines a vacuum space 2 within which a pair of electrodes 8 and 9 are axially disposed as described above in relation to FIG. 1. The shield 62 has a fixed cylindrical portion 63 with windows 66 and internal shutters or covers 65 adapted to cover the windows 66. In the released position of FIG. 10, these covers register with openings 66 to complete the shield. In the raised position of FIG. 12, they are out of registration with the windows 66 and permit inspection of the electrodes.

The fixed portion of the shield 64 is disposed coaxially with the electrodes 8 and 9 and substantially encloses the arcing surfaces thereof as shown in FIG. 10. Conducting material vaporized on motion of said electrodes from circuit-making to circuit-breaking relation thus tends to condense upon the shield rather than on the inside face of the envelope 1.

The movable portion of the shield 64 is comprised of covers of shutters 65. As shown, these are disposed in close proximity to the inside face of the fixed shield portion 63 of the shield 62 and are adapted to register with and completely cover the openings 66 in the fixed portion of the shield. A crank arm 67 is affixed to each shutter portion 65 and is pivotally supported from the inside face of the fixed shield part 63 by the respective pin 67a, FIG. 13. Each shutter 65 is thus movable between the active shielding position of FIG. 10 and the lifted viewing position of FIG. 12.

The upper movable electrode 6, FIG. 10, is provided with an annular collar member 68 positioned slightly above the head portion 8 of said electrode. The collar 68 extends radially outward a distance sufficient to engage the crank arms 67 when the electrode is lifted as shown in FIG. 12. In such event, the collar 68 engages and thereby rotates each of the crank arms 67, and hence shutter 65. The shutters are then lifted out of registration with the openings 66 in the fixed shield 63, thereby permitting viewing of the electrodes 8 and 9 for inspection.

Upon reposition of the electrode 6 to the position of FIG. 10, the collar 68 releases crank arms 67 and the movable shutters 65 drop back to registration with the openings 66 in the fixed shield part 63. The parts are thus positioned in their active, shielding positions.

FIG. 11 is a cross-section view through axis 11-11 of FIG. 10, showing the overhanging relationship between the crank arms 67 and the collar 68.

In the apparatus of FIGS. 10-13, the movable electrode rod 6 has three operating positions. The first position (not shown) is the fully lowered position, where electrode 8 is in contact-making relation with electrode 9. This is the normal circuit-conducting position. In this position, the collar 68 is out of contact with the crank arms 67 and the shutters are in the vertical, window covering position shown in FIG. 10. The second position of the movable electrode rod 6 is that shown in FIG. 10. This is the circuit-opening position. When the switch is carrying current, movement of the electrode rod 6 from the circuit-making to the circuit-breaking position of FIG. 10 normally gives rise to an arc between the electrodes that persists until natural current zero. It is this arc that produces the vaporized electrode material that tends to condense on the insulating walls of the vacuum envelope 1. Since the shutters 65 are in the vertical, shielding position with the electrode rod 6 raised as shown in FIG. 10, the full shield 64 is effective at this time to prevent condensation of conducting material on the insulating walls of the envelope 1. The third position of the movable electrode rod 6 is the shutter-lifting position of FIG. 12. In this position, the electrode rod 6 is lifted beyond

its circuit-breaking position of FIG. 10. This further movement can only take place when the circuit is interrupted, and hence cannot occur when there is metal vapor produced in the envelope 1. As shown in FIG. 12, the further movement of that figure is sufficient to raise the shields 65 to clear the windows 66 and permit visual inspection of the electrodes 8 and 9.

In FIGS. 14 and 15 a fixed gap vacuum device is shown in vertical section. The device of FIG. 14 includes an evacuable envelope 70 containing electrodes 71 and 72 defining a gap 73. The enclosure is evacuated to a pressure of 10^{-4} mm. Hg or less and preferably less than 10^{-5} mm. Hg. This device may be used as a spark gap, a lightning arrester or as a triggered vacuum gap. A protective shield 74 rests upon insulating member 75 within envelope 70 and is slidably movable along the longitudinal axis of the device. Motion between the protecting position, shown in FIG. 14, and the viewing position, shown in FIG. 15, may be effectuated by inverting the device so that shield 74 slides by gravity and exposes the electrodes for viewing.

While I have shown and described specific embodiments of the present invention, it will of course be understood that various modifications and alternative constructions may be made without departing from the present invention. I therefore intend by the appended claims to cover all such modifications and alternative constructions falling within their true spirit and scope.

What I claim as new and desired to secure by Letters Patent of the United States is:

1. A vacuum switch comprising in combination: an envelope defining a vacuum space and composed at least in part of a transparent body through which the interior of the space may be viewed; a pair of electrodes within the vacuum space, and movable between a spaced circuit-breaking relation and a containing circuit-making relation, said electrodes being active on motion from the circuit-making to circuit-breaking relation to generate vaporized conducting material that tends to condense in a conducting coating on the inside face of said part of the envelope, said electrodes being positioned within the envelope in locations viewable from outside the envelope and through said part of the envelope; movable opaque shield means located between the inside face of the envelope and the electrodes, said shield means being movable independent of the circuit-making and circuit-breaking movements of said electrodes between an active position in registration with and protecting said part of the envelope and a viewing position out of registration with said part of the envelope to permit viewing of the electrodes; and means outside the envelope operable to move the shield means at will between the active and viewing positions.

2. A vacuum switch comprising in combination: a cylindrical envelope having an axis, defining a vacuum space having an interior cylindrical face, and composed at least in part of a transparent body through which the interior of the space may be viewed; a pair of electrodes within the vacuum space, and movable in relation to each other and in the direction of said axis between an axially spaced circuit-breaking relation and an axially contacting circuit-making relation, said electrodes being active on motion from the circuit-making to the circuit-breaking relation to generate vaporized conducting material that tends to condense in a conducting coating on the inside face of said part of the envelope, said electrode being positioned within the envelope in locations viewable from outside the envelope and through said part of the envelope; an axially movable opaque means telescopically received in said envelope, in juxtaposition with said face, and adapted to move axially therein, said shield means being movable between an active position in registration with and protecting said part of the envelope and a viewing position out of registration with said part of the envelope to permit viewing of the electrodes; and means

operable from outside the envelope to move the shield means at will relative to said electrodes between the active and viewing positions.

3. A vacuum switch comprising in combination: an envelope having a wall portion defining a vacuum space having an inside face and composed at least in part of a transparent body through which the interior of the space may be viewed; a pair of electrodes within the vacuum space and movable between a spaced circuit-breaking relation and a contacting circuit-making relation, said electrodes being active on motion from the circuit-making to circuit-breaking relation to generate vaporized conducting material that tends to condense in a conducting coating on the inside face of said part of the envelope, said electrodes being positioned within the envelope in locations viewable from outside the envelope and through said part of the envelope; movable opaque shield means located between the inside face of the envelope and the electrodes, said shield means being movable between an active position in registration with and protecting said part of the envelope and a viewing position out of registration with said part of the envelope to permit viewing of the electrodes, at least a part of the shield means during such movement being constructed and arranged to move in a path generally parallel and adjacent to the inside face of the envelope, the shield means further defining magnetic armature elements at said part; and magnet means disposed outside the envelope and adapted to register with the armature to move the shield means relative to said electrodes between the active and viewing positions.

4. A vacuum switch comprising in combination: a cylindrical envelope having an axis, defining a vacuum space having an interior cylindrical face, and composed at least in part of a transparent body through which the interior of the space may be viewed; a pair of electrodes within the vacuum space, and movable along said axis in relation to each other between an axially spaced circuit-breaking relation and an axially contacting circuit-making relation, said electrodes being active on motion from the circuit-making to the circuit-breaking relation to generate vaporized conducting material that tends to condense in a conducting coating on the inside face of said part of the envelope, said electrodes being positioned within the envelope in locations viewable from outside the envelope and through said part of the envelope; a pair of axially movable opaque shields telescopically received in said envelope and adapted to move axially therein, said shield means being movable relative to said electrodes between an active position in end-to-end relation and protecting said part of the envelope and a viewing position with end-to-end spacing to permit viewing of the electrodes; and means operable from outside the envelope to move the pair of shields at will between the active and viewing positions.

5. A vacuum switch comprising in combination: an envelope defining a vacuum space and composed at least in part of a transparent body through which the interior of the space may be viewed; a pair of electrodes within the vacuum space, and movable between a spaced circuit-breaking relation and a contacting circuit-making relation, said electrodes being active on motion from the circuit-making to circuit-breaking relation to generate vaporized conducting material that tends to condense in a conducting coating on the inside face of said part of the envelope, said electrodes being positioned within the envelope in locations viewable from outside the envelope and through said part of the envelope; two-part movable opaque shield means located between the inside face of the envelope and the electrodes, one part of said shield means being in fixed position and disposed between the electrodes and the envelope to protect portions of the envelope from condensation of vaporized electrode material and defining a window in registration with said part of the envelope and through which the electrodes

may be viewed, the other part of said shield means being a cover for said window movable between an active position in registration therewith and protecting said part of the envelope and a viewing position out of registration with said window to permit viewing of the electrodes; and means operable from outside the envelope to move the shield means at will relative to said electrodes between the active and viewing positions.

6. A vacuum switch comprising in combination: an envelope defining a vacuum space having an inside face, and composed at least in part of a transparent body through which the interior of the space may be viewed; a pair of electrodes within the vacuum space, and movable between a spaced circuit-breaking relation and a contacting circuit-making relation, said electrodes being active on motion from the circuit-making to circuit-breaking relation to generate vaporized conducting material that tends to condense in a conducting coating on the inside face of said part of the envelope, said electrodes being positioned within the envelope in locations viewable from outside the envelope and through said part of the envelope, at least one of said electrodes being additionally movable beyond the circuit-breaking relation; means to move the electrodes between circuit-making and circuit-breaking relation to make and break the circuit and, at will, to move said one electrode beyond circuit-breaking relation, movable opaque shield means located between the inside face of the envelope and the electrodes, said shield means being movable between an active position in registration with and protecting said part of the envelope and a viewing position out of registration with said part of the envelope to permit viewing of said electrodes; said one electrode and said shield means having interchanging conformations effective to engage and move the shield to viewing position when said electrode is moved beyond circuit-breaking position.

7. A vacuum switch comprising in combination: an envelope defining a vacuum space and composed at least in part of a transparent body through which the interior of the space may be viewed; a pair of electrodes within the vacuum space, and movable between a spaced circuit-breaking relation and a contacting circuit-making relation, said pair of electrodes being active on motion from the circuit-making to circuit-breaking relation to generate vaporized conducting material that tends to condense in a conducting coating on the inside face of said part of the envelope, said electrodes being positioned within the envelope in locations viewable from outside the envelope and through said part of the envelope; a movable opaque shield located between the inside face of the envelope and the electrodes, said shield means being movable relative to said electrodes between an active position in registration with and protecting said part of the envelope and a viewing position out of registration with said parts of the envelope to permit viewing of the electrodes in response to means external of said envelope.

8. A vacuum gap device comprising in combination: an envelope defining a vacuum space and composed at least in part of a transparent body through which the interior of said space may be viewed; a pair of electrodes within the vacuum space adapted to form therebetween a vacuum gap for sustaining a high current electric arc, said electrodes upon the sustaining of an electric arc being the source of vaporized conducting material that tends to condense in a conducting coating upon the inside face of said part of the envelope, said electrodes being positioned within the envelope in locations viewable from outside the envelope and through said part of the envelope; movable opaque shield means located between the inside face of the envelope and the electrodes, said shield means being movable relative to said envelope and said electrodes between an active position in registration with and protecting said part of the envelope and a viewing position out of registration with said part of the envelope to permit

a viewing of the electrodes in response to means external of said envelope.

9. A vacuum gap device comprising in combination: a cylindrical envelope having an axis, defining a vacuum space having an interior cylindrical face, and composed at least in part of a transparent body through which the interior of the space may be viewed; a pair of electrodes within the vacuum space adapted to define therebetween a vacuum gap for sustaining a high current electric arc in vacuo, said electrodes being the source during arcing of vaporized conducting materials that tends to condense in a conducting coating on the inside of said part of the envelope, said electrodes being positioned within the envelope at locations viewable from outside the envelope and through said part of the envelope; an axially movable opaque means telescopically receivable in said envelope in juxtaposition with said face and adapted to move axially relative to said envelope and said electrodes, said shield means being movable between an active position in registration with and protecting said part of the envelope and a viewing position out of registration with said part of the envelope to permit viewing of the electrodes, said motion being in response to means external of said envelope.

10. A vacuum gap device comprising in combination: an envelope defining a vacuum space and composed at least in part of a transparent body through which the interior of said space may be viewed; a pair of fixed electrodes within the vacuum space adapted upon the application of an overvoltage to sustain a high current electric arc, said electrodes upon sustaining of an electric arc being the source of vaporized conducting material that tends to condense in a conducting coating upon the inside face of said part of the envelope, said electrodes being positioned within the envelope in locations viewable from outside

the envelope and through said part of the envelope; movable opaque shield means located between the inside face of the envelope and the electrodes, said shield means being movable between an active position in registration with and protecting said part of the envelope and a viewing position out of registration with said part of the envelope to permit a viewing of the electrodes, said motion being in response to the force of gravity acting on said shield.

11. A vacuum gap device comprising in combination: a cylindrical envelope having an axis, defining a vacuum space having an interior cylindrical face, and composed at least in part of a transparent body through which the interior of the space may be viewed; a pair of fixed electrodes within the vacuum space adapted upon an application of an overvoltage to sustain a high current electric arc, said electrodes being the source during arcing of vaporized conducting material that tends to condense in a conducting coating on the inside of said part of the envelope, said electrodes being positioned within the envelope in locations viewable from outside the envelope and through said part of the envelope; and axially movable opaque means telescopically receivable in said envelope in juxtaposition with said face and adapted to move axially therewith, said shield means being movable between an active position in registration with and protecting said part of the envelope and a viewing position out of registration with said part of the envelope to permit viewing of the electrodes, said motion being in response to an externally applied force.
